UNITED STATES PATENT OFFICE.

NICHOLAS S. VEDDER, OF TROY, AND TOBIAS S. HEISTER, OF LANSINGBURG,
ASSIGNORS TO NICHOLAS S. VEDDER, OF TROY, NEW YORK.

DESIGN FOR A COOKING-STOVE.

Specification forming part of Design No. 7,010, dated December 2, 1873; application filed September 12, 1873.
[Term of Patent 3½ years.]

To all whom it may concern:

Be it known that we, NICHOLAS S. VEDDER, a resident of Troy, in the county of Rensselaer and State of New York, and TOBIAS S. HEISTER, a resident of Lansingburg, in said county and State, have jointly invented and produced a new and original ornamental Design for Cooking-Stoves, of which the following is a specification, reference being had by letters to the accompanying engraving of a cooking-stove which embodies our said new design.

One part of our invention consists of the design for the compound ornament N for the panel of an oven-door, having the lower part extending forward of the upper portion, the said compound ornament being composed of an oval shield, having in its upper and lower parts upright plates of graduated lengths, and across its middle a horizontal band with a beaded border, and a central raised bar with inclined sides and ends; and the said oval shield being arranged upon a back piece having arched scroll-work ornamentations at top and bottom, and scalloped knob-like ornamentations on the sides, and a branch bearing leaves and flowers, and projecting forward from the lower part, and the whole being shaped, and ornamented, and arranged so as to appear substantially as represented in the aforesaid engraving.

Another part of our invention is the design for the large oven-door, consisting of the compound ornament N, composed and arranged on the panel O, substantially as above specified, and shown in the accompanying engraving, in combination with the compound border P, composed of the two united outside curved moldings and the adjacent inner scalloped or pointed edging, shaped and arranged so as to appear substantially as represented in the aforesaid engraving.

Another part of our invention consists of the design for the rectangular door or panel Q, as distinguished by the central compound ornament r, composed of the oval vertically-ribbed shield, crossed by a horizontal beaded band with projecting longitudinal bar, and the lateral and top and bottom ornamentations, in combination with the compound border s, com-

posed of the two united outer convex moldings and the inner pointed edging, all shaped, ornamented, and disposed so as to appear substantially as represented in the aforesaid engraving.

Another part consists of the design for the front door T, composed of the plain curved tablet u, having a horizontal bottom, upright parallel ends, and arched top, and surrounded by the compound border v, consisting of the two united outer convex moldings and the immediately contiguous pointed inner edging, of which each pointed part has upon it a bead or round projection, and the whole shaped and arranged together so as to appear as shown in the aforesaid engraving.

Another part consists of the design for the upper front plate w, as distinguished by the curved forwardly-projecting uppermost part x, the plain surface y, and the oblong rectangular panels z z, arranged upon the end portions thereof, and having the borders a a, each composed of the outer convex molding and the inner pointed edging, and the whole shaped and arranged together substantially as shown in the aforesaid engraving.

Another part consists of the design for the legs C, as distinguished by the central ornament thereon, composed of the horizontal projecting bar with inclined sides and ends upon an oval shield-like portion, having lateral and top and bottom ornaments thereon, and arranged upon a convex panel having flaring sides and a double-arched top, inclosed by an ornamental molding, and the whole shaped and arranged so as to appear substantially as represented in the accompanying engraving.

What we claim as our joint invention is—

1. The design for the compound ornament N, composed of the several parts herein specified, shaped and arranged together and upon the panel O, having its lower part extended forward of its upper portion, substantially as represented in the accompanying illustrative engraving.

2. The design for the oven-door, consisting of the compound ornament N, composed, shaped, and arranged on the panel O, in combination with the compound border P, composed of the outer moldings and inner scalloped or pointed

edging, all substantially as described herein, and shown in the aforesaid engraving.

3. The design for the rectangular panel or door Q, consisting of the central compound ornament r and the compound border s, each composed, and all shaped and arranged together, substantially as shown and described.

4. The design for the front door T, consisting of the plain curved tablet u, having the arched top, and the compound border v, composed of the two united convex outer moldings and the inner pointed mat or edging, with a bead or rounded projection on each projecting pointed portion, as shown in the aforesaid engraving.

5. The design for the upper front plate w,

composed of the curved projecting part x, plain curved surface y, and the oblong rectangular panels z z, surrounded by the borders a a, each composed of the outer convex molding and the inner pointed matting, all shaped and disposed substantially as shown and described.

6. The design for the leg C, composed, shaped, and arranged as specified, and shown in the accompanying illustration.

NICHOLAS S. VEDDER.
TOBIAS S. HEISTER.
